UNITED STATES PATENT OFFICE.

JOHN L. DAHL, OF TEANECK, NEW JERSEY.

STAKE-POCKET.

1,397,725.

Specification of Letters Patent.

Patented Nov. 22, 1921.

Application filed January 18, 1921. Serial No. 438,101.

To all whom it may concern:

Be it known that I, JOHN L. DAHL, a citizen of the United States, residing at Teaneck, in the county of Bergen and State of New Jersey, have invented certain new and useful Improvements in Stake-Pockets, of which the following is a specification.

This invention relates to stake pockets, such as are used on railway flat cars for retaining on the cars lumber, logs, poles, or other long or bulky articles.

One of the objects of this invention is to provide a pocket for supporting an upright stake in such a manner that to open the pocket and release the stake requires a minimum amount of effort and danger to the operator, as well as a minimum likelihood of damage to the structure itself.

Another object of the invention is to simplify as much as possible the construction, thereby enabling me to provide a device at a relatively low cost and one that will be most practical and efficient in practice.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view of my improvement with the gate closed, but with a dotted line showing of the gate partially open.

Fig. 2 is a side elevation of the same, partly in section on the line 2—2 of Fig. 3, the latch being indicated in dotted lines in elevated or releasing position.

Fig. 3 is a front elevation, the position of the stake being indicated in dot and dash lines.

Referring now more specifically to the drawings I illustrate my improvement as comprising but three main parts,—viz., the receptacle 10, the gate 11, and the latch 12.

The receptacle consists of a box like structure including a flat vertical rear wall 13, two parallel vertical side walls 14 and 15 perpendicular to the rear wall, and a bottom 16. The front, except as soon to be noted, is open as are also the lower front corner portions of the sides. The rear wall is provided with lateral projections or

flanges 17 constituting reinforcements for the structure, and the upper ends of these flanges merge into laterally projecting ears 18 for fastening members 19. Adjacent to the side wall 15 but spaced somewhat therefrom is another wall 20, the space between the walls 15 and 20 serving as a housing for the latch 12. This housing includes a bottom or shelf 21 next to the rear wall, and a reinforcing member 22 near its front end, the space between these parts 21 and 22 being reserved for the purpose of free passage of rain, snow, or other extraneous matter.

The gate 11 is a substantially flat member, having at one end a knuckle 23 bearing between two lugs or ears 24 formed on the front upper edge of the wall 14, and a vertical pivot pin 25 completes the hinge for the gate providing for the swinging thereof around the vertical axis of the pin 25. The end of the gate remote from the hinge constitutes a projecting nose 26, which in the normal closed position of the gate rests upon a lug 27 extending forward from the upper front portion of the wall 15. Directly above this lug 27 the wall 15 is provided with an extension 28 which prevents any possibility of the gate being forced upward at any time such as during the unlatching operation. In the closed position of the gate the nose 26 thereof bears against the front wall 29 of the latch box.

The latch 12 is pivoted between the walls 15 and 20 upon a horizontal pivot pin 30 extending through said walls and having its head countersunk preferably in the inner face of the wall 15. The latch is provided at its front end with a hook shaped head 31 engaging over the nose 26 of the gate holding the gate shut. The head 31 is beveled preferably to facilitate the automatic lifting of the latch while the gate is being slammed shut. The rear end of the latch is provided with an extension or tail piece 32, having two distinct functions, one of which is to accommodate one end of a strong coil spring 33 or its equivalent while the other end of the spring rests upon the shelf 21 between a pair of spaced lugs 34 and the rear wall 13 of the receptacle. The purpose of the spring is to hold the latch in closed position with its head engaging over the nose 26 of the gate, but yieldingly so held, permitting the opening of the gate by shoving or knocking upward of the outer

end of the latch to the dotted line position of Fig. 2. The other function of the tail piece is to coöperate with a shoulder 35 formed on the rear wall 13 to limit the upward swing of the latch and so prevent the displacement of the spring.

I claim:

1. In a stake pocket, the combination with a receptacle and a gate movable toward the receptacle into closed position, of a latch engageable over a portion of the gate to hold it in closed position, said latch being pivoted on a horizontal pivot to the receptacle and having a tail piece projecting rearward from the pivot, said tail piece serving to control the movement of the latch around its pivot.

2. A stake pocket as set forth in claim 1 in which the tail piece coöperates with a portion of the receptacle to positively limit the upward swing of the latch in releasing the gate.

3. A stake pocket as set forth in claim 1 in which a spring coöperates with the tail piece to normally urge the front end of

the latch downward into position to engage over the gate.

4. In a stake pocket, the combination of a receptacle having an open front, a gate movable toward the receptacle to close the open front, the receptacle having at one side a housing, a latch pivoted within the housing and extending thence forward over the top of the gate to hold the gate closed, the housing being provided with a shelf at its bottom and adjacent to the rear wall of the receptacle, the latch having a tail piece projecting rearward from its pivot over said shelf, and a spring located between the shelf and the tail piece and tending to hold the front end of the latch down in engaging position.

5. A stake pocket as set forth in claim 4 in which there is provided at the rear end of the housing a rigid shoulder coöoperating with the tail piece to limit the compression of the spring and the upward swing of the front end of the latch.

In testimony whereof I affix my signature.

JOHN L. DAHL.
